1,599,100

Patented Sept. 7, 1926.

UNITED STATES PATENT OFFICE.

FRANCIS M. ROGERS AND MAX G. PAULUS, OF WHITING, INDIANA, ASSIGNEES TO
STANDARD OIL COMPANY, OF CHICAGO, ILLINOIS, A CORPORATION OF INDIANA.

IMPROVEMENT IN PYROGENETIC MANUFACTURE OF GASOLINE.

No Drawing.

Application filed July 21, 1919. Serial No. 312,400.

In the manufacture of gasoline by pyrogenesis where the gasoline is distilled and condensed under pressure, as for example in accordance with the process of Patent 5 1119700, it has heretofore been the practice to take the gasoline from the receiving drum from which it emerges under pressure and with a considerable quantity of gas dissolved in it, and flow the gasoline into a 10 receptacle at atmospheric pressure wherein the dissolved gas bubbles out.

We have discovered that a considerable economy can be effected by conducting the gasoline while still under pressure into a 15 receptacle under like pressure, and leaving within that receptacle a vapor or gas filled space above the liquid body. The pressure is then reduced by opening a valve in the upper part of the receptacle permitting the 20 escape of gas therefrom so that the gas is separated from the liquid while still under pressure and is allowed to escape only after such separation. In this way the bulk of the gas leaves the receptacle at high pressure, and it is only at the very end of the 25 gas release that any gas at a pressure approximating that of the atmosphere leaves the surface of the liquid.

The process may be practiced in apparatus of any form, all that is required being 30 a tank into which a charge of the liquid may be introduced and a gas escape valve in the upper part thereof. For this reason

it has been deemed unnecessary to illustrate any specific apparatus, that portion 35 of the apparatus which is used in the distillation being of well known form, and the portion used in our method of gas separation being of very rudimentary form.

We claim:

1. The herein described improvement consisting in conducting pyrogenetic distillation of a hydrocarbon oil of relatively high boiling point, condensing the gasoline containing distillate in a condenser in communication with the still and under still pressure, isolating the liquid distillate, permitting the gas dissolved in the distillate to pass out of the distillate while under pressure, and releasing the gas upon such separation with a gradual reduction of pressure.

2. The herein described improvement consisting in conducting the pyrogenetic distillation of high boiling point hydrocarbon oil under pressure and condensing the light gasoline containing distillate formed also under pressure whereby the distillate contains gas in solution, separating the liquid under pressure, providing a vapor space 55 thereabove and gradually releasing the gas from said vapor space, thereby gradually reducing said pressure.

FRANCIS M. ROGERS.
MAX G. PAULUS.
